UNITED STATES PATENT OFFICE.

NATHAN G. ANGLE, OF FREEPORT, ILLINOIS.

WINDOW-SCREEN.

No. 805,113.

Specification of Letters Patent.

Patented Nov. 21, 1905.

Application filed June 9, 1905. Serial No. 264,528.

To all whom it may concern:

Be it known that I, NATHAN G. ANGLE, a citizen of the United States of America, residing at Freeport, in the county of Stephenson and State of Illinois, have invented certain new and useful Improvements in Window-Screens, of which the following is a specification.

My invention relates to improvements in removable window-screens; and the invention 10 consists of the particular construction, arrangement, and combination of parts herein-after fully described, and specifically pointed out in the claims.

Referring to the accompanying drawings, 15 which form a part of this specification, Figure 1 is a view in isometrical perspective of a screen embodying my invention. Fig. 2 is a section at the dotted line 2 2 in Fig. 1 of the same seated and secured in a window-frame. Fig. 3 is an enlarged detail of the locking devices of the screen. Fig. 4 is a section at the 20 dotted line 4 4 in Fig. 3 of parts there shown. Fig. 5 is a section at the dotted line 5 5 in Fig. 4 of parts there shown.

Like letters of reference indicate corresponding parts throughout the several views.

A is a rectangular screen-frame formed of upper and lower rails A' A² and stiles A³ A⁴, securing them together. The frame is provided with ordinary wire or any desired screen-cloth A⁵, attached thereto in the usual manner.

B is a rectangular leaf of the same length as the stiles of the frame and of any desired width, provided with transverse parallel locking-arms B' B², substantially the same distance apart as and adapted to lap over upon the arms A' A² and hinged by one side thereof at b to one of such stiles A³ A⁴.

C represents buttonholes in the locking-arms B' B² and are provided with correspondingly-slotted face-plates C', applied and fastened thereover by means of screws C².

D represents long-shanked buttons having oppositely-inclined cams D' D² formed thereon to engage the face-plates C' of the buttonholes C and rotatably mounted by their shanks D³ in the base-plates D⁴, which are countersunk into and secured to the rails A' A² of the screen-frame by means of screws D⁵.

a is the sill of a window-frame provided 50 with sides a', having grooves a² a³ therein for the reception of window-sash.

In order to place my improved window-screen in proper position in a window-frame, the lower sash should be raised a distance 55 equal to the height of the screen, and the latter is then inserted into the vertical grooves a² in the frame, as indicated by dotted lines in Fig. 2, the screen and its leaf B, when extended and lying in the same plane, equaling 60 the width of the window-frame plus the depths of the grooves a² therein. The locking-arms B' B² are secured to the rails A' A² of the screen-frame by inserting the buttons D through the buttonholes C in such arms B' B² 65 and turning such buttons to the position shown in Fig. 3, thereby causing the cams D' D² on the same to closely engage the face-plate C' thereon.

Having fully described my invention, what 70 I claim as new, and desire to secure by Letters Patent, is—

In a window-screen, in combination, a screen-frame, formed of upper and lower rails A' A² and stiles A³ A⁴ securing them together and 75 provided with screen-cloth attached thereto, a leaf B provided with transverse parallel locking-arms B' B², substantially the same distance apart as and adapted to lap over upon the rails A³ A⁴, and hinged, at b, to one of 80 such stiles, as A⁴, the locking-arms B' B² having buttonholes C therein provided with face-plates C' applied and fastened thereover, and buttons D having oppositely-inclined cams D' D² formed thereon to engage the face-plates 85 C' of the buttonholes C and rotatably mounted, by their shanks, in base-plates D⁴ countersunk into and secured to the rails A' A² of the screen-frame, substantially as described and for the purpose specified. 90

In testimony whereof I have signed my name to this specification in the presence of two subscribing witnesses.

NATHAN G. ANGLE.
